Primary Examiner — Sandra Morris(74) Attorney, Agent, or Firm — Davis & Bujold, PLLC;
Michael J. Bujold(57) CLAIM

I claim the ornamental design for a roulette game, as shown and described.

DESCRIPTIONFIG. 1 is a top plan view of a first embodiment of my new design for the roulette game; and,
FIG. 2 is a top plan view of a second embodiment of my new design for the roulette game.

The bottom plan, the front, the rear, the left side and the right side views of the roulette game do not from any part of the claimed design.

1 Claim, 2 Drawing Sheets Fig. 1.
